UNITED STATES PATENT OFFICE

ANDRÉ LÉON VICTOR CLEMENT DEBRIE, OF PARIS, FRANCE

SHUTTER FOR CINEMATOGRAPHIC APPARATUS

Application filed February 10, 1928, Serial No. 253,474, and in France February 21, 1927.

My invention has for its object an improved shutter for cinematographic apparatuses which allows the film to be impressed or exposed automatically to a degree which is constant whatever the speed of rotation of the mechanism of the cinematographic apparatus.

In view of this the shutter instead of being constituted by the usual single indented disc comprises two preferably similar indented discs disposed side by side and of which one is keyed on the usual controlling shaft and the other is mounted freely on its shaft which is driven by the former one and may 15 rotate with reference to it under the action of a device submitted to the influence of the centrifugal force in a manner such that at the greater speeds, the indentations of the two discs are in complete coincidence so that 20 the maximum amount of light may pass through them. On the contrary as the apparatus moves more slowly, the indentations are shifted more and more one with reference to the other so as to cause the amount of light 25 passing through the shutter to diminish when the speed decreases.

I have shown by way of example on appended drawings a form of execution of my invention wherein:

30 Fig. 1 is a general view of the device when at rest,

Fig. 2 is a diagrammatical side view partly sectional of a centrifugally acting part respectively in its operative and its inoperative 35 position.

Fig. 3 is a partly sectional side view at an enlarged scale.

Fig. 4 shows two half sections taken at 40 90° with reference to Fig. 3, the upper half-section showing the device in its inoperative position and the lower half-section showing it at midway between its extreme positions.

The shutter comprises two indented discs 1 and 3 of which the former is keyed 45 to the controlling shaft 2 and the latter is secured to a sleeve 4 freely mounted on the shaft 2 and abutting against the disc 1. The two discs may be more or less identical so that under certain conditions to be ascertained hereinafter, their indentations may be

in perfect coincidence. The discs 1 and 3 may however not be exactly similar as shown. On the inside of the disc 1 are disposed in alignment with each other two threaded rods having a great pitch, and rotatably held in 55 the bearings 7 and 8 secured to the disc 1, the axis of the two rods passing through the center of rotation of the disc. To each rod and near the said center is keyed a bevel pinion 9 or 10.

Besides two nuts 11 and 12 are adapted to slide along the two rods and their shape is such that they cannot rotate round the latter. The nuts are connected together through the 60 springs 13 and 14 and engage the threads of 65 rods 5 and 6 either through suitable tappings or through a projection such as 15.

Lastly in a recess 16 provided in the center of the disc or plate 3 is secured a bevel pinion 17 engaging the bevel pinions 9 and 10 70 whereby when rotating the disc 3 moves together with the disc 1; a pin 18 passing through the shaft 2 keeps the disc 3 in contact with the disc 1.

The working is as follows: When at rest 75 the indentations of the two discs 1 and 3 are shifted one with reference to the other (Fig. 1) so as to leave only the minimum aperture allowed for the shutter. When the shaft 2 rotates, it draws the disc 1 along with it and 80 also the disc 3 through the pinions 9 and 10 and pinion 17. As the speed of shaft 2 increases, the nuts 11 and 12 have a tendency under the action of the centrifugal force to move away from the center and as they cannot rotate they cause the threaded rods 5 and 6 to rotate in opposite directions and consequently the pinions 9 and 10 to revolve in opposite directions. The latter mesh with the wheel 17 which rotates and causes the disc 90 3 to rotate with reference to the shaft 2 and the disc 1 in a direction such that the aperture afforded by the shutter increases. For a sufficient speed of the shaft, the two indentations of the discs are in coincidence and the 95 shutter opening is maximum. A stop 19 borne by the disc 3 is adapted to meet at this moment the edge of the disc 1 so as to prevent when the speed increases further, the 100 relative rotation of the discs from continu-

ing. If this were the case the opening of the shutter would then diminish by a shifting in the reverse direction of the indentations of the discs. The same result could 5 also be obtained by making the nuts 11 and 12 abut against the bearings 8.

The springs 13 and 14 have a tendency to bring back the two discs towards their initial position when the speed decreases and consequently to close the shutter aperture.

10 What I claim is:

1. A shutter for cinematographic apparatuses comprising a driving shaft, a first indented disc keyed thereto, a second indented disc, mounted freely on the driving shaft, the indentations of the discs being normally in only partial coincidence, two alined threaded rods rotatably secured to the first disc, over a diameter thereof, a bevel pinion 15 keyed to the inner end of each rod, a toothed pinion coaxial with and keyed to the second disc and meshing with the two bevel pinions, a longitudinally movable nut cooperating with each rod, means for preventing the 20 said nuts from rotating, and springs urging the nuts together.

2. A shutter for cinematographic apparatuses comprising a driving shaft, a first indented disc secured thereto, a second indented disc mounted freely on the driving shaft, the indentations of the discs when at 25 rest being in only partial coincidence, a gear work connecting the two discs and adapted to make them rotate together and an 30 independent centrifugal device slidably mounted with reference to the first disc and positively controlling the gear work for shifting the second disc angularly with reference to the first one.

3. A shutter for cinematographic apparatuses comprising a driving shaft, a first indented disc secured thereto, a second indented disc mounted freely on the driving shaft, the indentations of the discs when at 35 rest being in only partial coincidence, a nut adapted to slide radially over the first disc under the action of the centrifugal force, a spring urging said nut back, a long-pitched threaded rod rotatably supported by the 40 first disc and cooperating with the nut, and means for positively controlling the angular position of the second disc on the shaft through the rotation of the threaded rod.

45 In testimony whereof I have signed my name to this specification.

ANDRÉ LÉON VICTOR CLEMENT DEBRIE.
